HANGING DEVICE FOR SCREENS

Filed July 20, 1926

INVENTOR

Munn & Co.
ATTORNEY

UNITED STATES PATENT OFFICE.

RUSSELL SIDNEY HOLCOMB, OF LOS ANGELES, CALIFORNIA.

HANGING DEVICE FOR SCREENS.

Application filed July 20, 1926. Serial No. 123,667.

My invention relates to a device particularly adapted, although not necessarily, for supporting and securing a window screen in position to span the opening in a window frame, and which operates to maintain the screen snugly in engagement with the frame so as to prevent rattling and displacement of the screen, the device greatly simplifying the application of the screen to the frame and being applied at the inner side of the screen so that the outside appearance of the window frame and screen will not be detracted from by unsightly fittings.

It is a further purpose of my invention to provide a device of this character which is inexpensive to manufacture; is thoroughly reliable and positive in operation and is easily installed; and which forms a hinged connection between the screen and frame so as to permit outward swinging movement of the screen, thus providing access to the outer side of the window panes for cleaning and without the danger of the screen accidentally becoming detached from the window frame and dropping from the latter, the device operating automatically upon the release of the screen to restore the latter to and maintain it in closed position.

I will describe only one form of hanging device for screens embodying my invention, and will then point out the novel features thereof in claims.

In the accompanying drawings,

Figure 1 is a view showing in side elevation one form of hanging device for screen embodying my invention in applied position with respect to a screen;

Figure 2 is a view similar to Figure 1 and showing the screen applied to a window frame and the device operating to secure the screen to the frame;

Figure 3 is a horizontal sectional view taken on the line 3—3 of Figure 2 and looking in the direction of the arrows;

Figure 4 is a vertical sectional view taken on the lines 4—4 of Figure 2 and looking in the direction of the arrows, and

Figure 5 is a perspective view of the device.

Referring specifically to the drawing in which similar reference characters designate similar parts in each of the several views, my invention in its present embodiment comprises a member designated generally at M and preferably constructed from a single

length of flexible wire to provide a pair of arms constituting oppositely disposed and offset linear portions 10 and 11 connected by a curled intermediate portion 12. The portion 11 is of greater length than the portion 10 and its free end is slightly curved laterally as shown at 13, while the free end of the portion 10 is curled upon itself to form an eye 14. It will be noted that the curled portion resiliently connects the arms and at 12 merges into the portion 10 while an abrupt bend 15 is formed at its point of juncture with the portion 11.

The installation and operation of the device is as follows:

The device is first positioned at the inner side of the frame F of a screen S as shown in Figure 1, it preferably being applied at the top portion of the frame but can as well be applied to the bottom portion or either of the sides of the frame. A fastening member such as for instance a roofing nail 16 is now extended through the eye 13 and then driven into the frame, care being taken that the nail is not driven in so far as to cause binding engagement of its head with the eye, to the end that the device will be free to rock about the eye as a pivot. With the device thus secured to the screen frame and occupying the inclined position with respect to the edge of the frame as shown in Figure 1, a second and similar fastening member 17 is now driven into the screen frame adjacent the free end and alongside of the portion 11. A headed fastening member 18 constituting a latching projection is then driven into the window frame W from the underside of its top stile so that a portion of the shank of the member remains projecting, care being taken to so position the fastening member that when the screen is mounted in the window frame in engagement with the usual shoulder 19 extending across the top and along the sides of the frame, the fastening member will be opposite the linear position 10 substantially at its point of connection with the portion 12 and will be offset inwardly with respect to the plane of the device. With the device positioned as shown in Figure 1 it is now flexed upwardly and away from the screen to the position shown in Figure 3 in which position the curled portion 12 will be placed under tension and the linear portion 10 will be disposed above and to the inner side of the fastening member 18. During this flexing move-

ment, the linear portion 10 will pivot on the fastening member 16 while the linear portion 11 will slide upon the shank of the fastening member 17.

5. Upon the release of the device its natural tendency to return to the normal position shown in Figure 1 will cause the linear portion 10 to bear against the shank and head of the fastening member 18 so that the device 10 will be latched to the member and will act to draw the screen upwardly and inwardly into snug engagement with the shoulder 19 of the window frame, thus firmly supporting and securing the screen in the frame.

15. From the foregoing operation of the device it will be clear that although the screen is firmly supported in the window frame it is free to be swung outwardly a sufficient amount to give access to the outer side of the 20 window panes for cleaning, the device providing a hinged connection with the window frame and being further flexed during the outward swinging movement of the screen so that when the latter is released the device will 25 operate to draw the screen again into snug engagement with the shoulder 19.

It is evident that one or more devices can be used on a screen, the number depending on the size of the screen, one generally being adequate for a relatively narrow screen. Furthermore, two or more of the devices can be positioned along one side of a screen for either a window or door so as to function as a hinge in permitting the window or door to be swung 35 to open position for the passage of persons, and operating when the screen is released to return the latter to closed position.

It will be manifest that my invention is capable of a wide range of use; can be effectively applied to closures wherever a spring hinged connection is desired; and will normally operate to yieldingly maintain a closure in closed position yet permitting movement of the closure to open position as the 45 occasion may require.

Although I have herein shown only one form of hanging devices for screens embodying my invention, it is to be understood that various changes and modifications may be 50 made therein without departing from the spirit of my invention and the spirit and scope of the appended claims.

I claim:

55. 1. A screen hanging device comprising a pair of resiliently connected and substantially

oppositely disposed arms, one of which is provided at its free end portion with an opening.

2. A screen hanging device comprising a member constructed from a single length of flexible wire to provide a pair of oppositely disposed linear portions resiliently connected at their confronting ends by a curled intermediate portion, the free end of one of the portions being bent to form an eye.

3. A screen hanging device comprising a member having a pair of substantially oppositely disposed arms connected at their confronting ends by a curled resilient portion, the free end of one of the arms having an eye through which a fastening member is adapted to be extended to secure the device to a screen while said one of the arms is adapted to be engaged intermediate its ends with a projection secured to a window frame and the other of the arms with a projection secured to the screen, all in such manner that the screen will be hung by the device in the window frame and normally urged to closed position by the device.

4. A screen hanging device comprising a member constructed from a single length of flexible wire coiled upon itself intermediate its ends to provide a resilient portion and linear portions extending in substantially opposite directions from the resilient portion, the free end of one of the linear portions having an eye through which a fastening member is adapted to be extended to secure the device to a screen while said one of the linear portions is adapted to be engaged with a projection secured to a window frame and the other of the linear portions with a projection secured to the screen, all in such manner that the screen will be hung by the device in the window frame and normally urged to closed position by the device.

5. A screen hanging device comprising a member constructed from a single length of flexible wire coiled upon itself intermediate its ends to provide a resilient portion and linear portions extending in substantially opposite directions from the resilient portion, one of the linear portions extending tangentially from the resilient portion and having an eye at its free end and the other of the linear portions being offset from the first linear portion and extending across the resilient portion.

RUSSELL SIDNEY HOLCOMB.
